(57) **CLAIM**

The ornamental design for head gear, as shown and described.

DESCRIPTION

FIG. 1 is a front view of head gear of the invention.

FIG. 2 is a side view of the head gear of FIG. 1.

FIG. 3 is a top view of the head gear of FIG. 1.

FIG. 4 is a bottom view of the head gear of FIG. 1.

FIG. 5 is a front perspective view of the head gear of FIG. 1 being worn by a user.

FIG. 6 is a side view of the head gear of FIG. 1 being worn by a user; and,

FIG. 7 is a rear view of the head gear of FIG. 1 being worn by a user.

The broken lines in the figures are for environmental purpose only and form no part of the claimed design.
